UNITED STATES PATENT OFFICE.

HENRY F. WEINLAND, OF SPRINGFIELD, OHIO, ASSIGNOR TO THE LAGONDA MANUFACTURING COMPANY, OF SPRINGFIELD, OHIO, A CORPORATION OF OHIO.

ROTARY MOTOR.

978,085.

Specification of Letters Patent.

Patented Dec. 6, 1910.

Application filed December 26, 1907. Serial No. 408,005.

To all whom it may concern:

Be it known that I, HENRY F. WEINLAND, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors, and especially to a motor of this character actuated by air or steam.

The object of my invention is to provide a motor of greater efficiency and steadiness 15 of power than the well-known one stage machine, and to that end I have invented a two stage motor, that is to say, one in which the actuating medium becomes effective twice in each revolution of the motor thus 20 insuring steadiness of power and greater efficiency in operation.

A further object is to so arrange the runner in its relation to the casing, as to take up wear and avoid loss of the actuating 25 medium.

With these and other objects in view, my invention consists of the construction and combination hereinafter described and set forth in the claims.

30 In the accompanying drawings, Figure 1 is a top plan view of a motor embodying my invention. Fig. 2 is a side elevation of same. Fig. 3 is a sectional plan view of exhaust head on line M M of Fig. 2, looking in the 35 direction of the arrows. Fig. 4 is a sectional plan view of inlet head taken on line O O of Fig. 2, looking in the direction of the arrows. Fig. 5 is a cross sectional view of inlet head taken on line Y Y of Fig. 4. Fig. 6 is an 40 end view of the runner and case taken on the line N N of Fig. 2, looking in the direction of the arrows, the exhaust head being removed. Fig. 7 is a cross section through motor on the line Z Z of Fig. 1. Fig. 8 is 45 a detail of paddle holding cage. Fig. 9 is a cross section of same. Figs. 10 and 11 show modifications of the paddle, the paddle being shown within the cage in Fig. 10. Fig. 12 is a cross section through the case 50 showing one inlet and exhaust port, the drawing being broken away showing the conduits leading to said ports.

In the drawings, *a* represents an exhaust head, *b* an inlet head and *c* the cylinder of

a casing forming a chamber in which a runner *d* is adapted to operate, the arrangement being such that the runner contacts with the walls of the chamber on opposite sides thereof, forming oppositely disposed crescent shaped chambers *c*² and *c*³ as particularly 55 shown in Fig. 6.

The chamber in which the runner is placed so as to form the two crescent shaped chambers, may be elliptical in form but I preferably arrange it in what I may term a three 60 circle chamber, that is to say, the inner walls of the chamber are so curved as to give a greater length of surface where the runner contacts with the wall, thus forming a better seal than would be given if the chamber 65 were in the form of a perfect ellipse. On opposite sides of these points of contact, I have arranged inlet ports *c*⁴ and exhaust ports *c*⁵ opening through conduits into the crescent shaped chambers as particularly 70 shown in Figs. 6 and 12. As the inlet and exhaust ports open in opposite sides of the casing and Fig. 6 is a view looking at exhaust side, the inlet ports in this view are shown in dotted lines. The actuating medium is 75 introduced through an opening *b*¹ in the head *b*, the supply hose coupling being screwed therein or connected in any suitable manner, and the conduits *b*² leading from said opening, register at their inner ends 80 with the ports *c*⁴, the arrangement being particularly shown in Figs. 4 and 5.

In the head *a*, I have shown conduits *a*¹ having a common outlet *a*², the inner ends of said conduits having openings *a*³ that 85 register with the exhaust port *c*⁵, said head and conduits being particularly shown in Figs. 1 and 3. The heads *a* and *b* and the cylinder *c* are secured together by bolts *c*⁶.

The runner *d* is mounted on a shaft *d*¹, 90 having a reduced end *d*² journaled in a recess of the head *b* and I preferably use a removable bushing *b*³ in said recess to form a bearing for the shaft. The forward end of the shaft extends through and is journaled in an opening in a central hub like portion *a*⁴ of the head *a*, and I preferably provide a removable bushing *b*⁴ in said opening to form a bearing for the shaft, said bushing having a shoulder at its inner end 95 to bear against a collar *d*⁰ on the shaft.

The outer end of the shaft I have shown square in form to receive a socket coupling

2
to transmit the power but any suitable coupling may be employed for this purpose. When the motor is used for driving a drill or tube cleaner, the end thrust is severe and 5 to meet this demand, I provide a collar d^{11} and a plurality of disks, two, being shown in the drawings between the collar and the hub a^4 . The collar is screw threaded on the shaft, and has a transverse slot d^{12} with a 10 set screw d^{13} , extending through said slot to pinch the collar on the shaft.

I have shown the runner with three radially movable paddles d^8 equally distant from each other, held within recesses in the runner 15 when passing the portions of the wall of the chamber that the runner is in contact with, and adapted as the runner rotates to move outwardly into the crescent shaped chambers to receive the pressure of the actuating 20 medium to rotate the runner, said pressure being admitted through the inlet ports and discharged through the exhaust ports hereinbefore described.

In Fig. 6, I have shown one of the paddles 25 at rest between an inlet port of one crescent chamber and the exhaust port of the other, and the runner rotating from right to left, the paddle following it is under pressure at about one-third its stroke, and the paddle 30 preceding it is under pressure at about two-thirds its stroke. Now when the first named paddle passes the inlet and takes pressure, it closes off the pressure from the preceding paddle, and each paddle successively operates 35 through the oppositely disposed chambers taking and exhausting the actuating medium in like manner to rotate the runner.

It will be seen that by providing two 40 working chambers and a runner with three paddles, I obtain a working distance of two-thirds of a revolution, whereas in a single stage motor taking steam at only one point, the working distance is only about one-half the revolution. This increase of 45 working distance in each revolution avoids dead centers, gives greater steadiness of motion and efficiency, and a motor of a given power can be built less in weight and smaller in compass than a single stage motor 50 of like power.

The paddles may be seated directly in recesses in the runner but I preferably employ removable cages d^4 having slots in which the paddles are seated. Said cages 55 are formed with oppositely disposed shoulders d^5 to hold them within recesses in the runner as particularly shown in Fig. 6. Ordinarily, the paddles will be thrown outwardly by centrifugal force but in the event 60 they should from any cause stick in the slot and become inoperative and allowing the actuating medium to waste through the chamber, I have provided the channels d^6 opening into the rear of slots behind the 65 paddles admitting the actuating medium

to positively force the paddles outwardly, the arrangement being clearly shown in Figs. 8 and 9.

I preferably make the length of the runner 70 slightly less than the length of the chamber in which it operates, and the runner is splined on the shaft as shown at d^{10} in Fig. 7 to admit of some longitudinal movement 75 to permit the thrust bearing to take the thrust and give the cylinder rings and paddles clearance to act.

The cylinder rings c^7 are recessed in each 80 side of the runner and are intercepted by the paddles or paddle cages when the cages are used. The rings are spring pressed by 85 springs c^8 in a well known manner to hold the rings against the casing and form a seal, and I preferably form the cages in sections the inner abutting ends of which have a shoulder d^7 so that when the actuating medium 90 forces the sections apart to keep the outer ends in contact with the casing, the shoulder d^7 will form a seal to prevent the escape of the actuating medium, and while 95 I have shown the paddles in a single plate or blade, these too may be made in sections and adapted to be pressed apart as shown in Figs. 10 and 11, the shoulder d^8 forming a seal in one direction and the oppositely disposed abutting reduced portions d^{14} being necessary when that portion of the paddle 100 having the abutting portions d^{14} have moved outwardly, and are operating through the working chambers. These sectional paddles and cages together with the cylinder rings form a complete continuous seal 105 between the sides of the runner and the casing. To reduce the bearing surface between the runner and the casing, I preferably form the heads a and b with slight 110 central recesses a^5 and b^5 as shown in Figs. 5 and 7.

Having thus described my invention, I claim:

1. In a rotatable motor such as described, 110 a casing and a runner with radially movable paddles and removable cages therefor having no radial movement, said cages being made in sections adapted to be forced apart by the actuating medium, the inner 115 ends having abutting shoulders to prevent the escape of the actuating medium, substantially as described.

2. In a rotatable motor such as described, 120 a casing and a runner with radially movable paddles and removable cages for said paddles seated in said runner and having no radial movement, sealing rings between the runner and casing intercepted by the cages, said cages being made in sections and 125 adapted to be forced apart by the actuating medium, the inner ends being arranged to form a seal to prevent the escape of the actuating medium, substantially as described.

3. In a rotatable motor such as described, a casing and a runner with radially movable paddles and removable cages for said paddles seated in said runner and having no radial movement, sealing rings between the runner and casing, intercepted by the cages, said cages and paddles each being made in sections adapted to be forced apart by the actuating medium, the inner ends of each having abutting shoulders to prevent the escape of the actuating medium, substantially as described.
4. In a rotatable motor such as described, a runner, a casing having a chamber therefor with inlet and exhaust ports, a driving shaft rotated by the runner but adapted to move longitudinally therethrough, radially movable paddles and removable cages for said paddles seated in said runner and having no radial movement, sealing rings between the runner and casing intercepted by the cages, said cages being made in sections and adapted to be forced apart by the actuating medium, the inner ends being arranged to form a seal to prevent the escape of the actuating medium and means to take

the end thrust of the shaft, substantially as described.

5. In a rotatable motor such as described, a runner, a casing having a chamber therefor with inlet and exhaust ports, a driving shaft rotated by the runner but adapted to move longitudinally therethrough, radially movable paddles and removable cages for said paddles seated in said runner and having no radial movement, sealing rings between the runner and casing intercepted by the cages, said cages and paddles each being made in sections adapted to be forced apart by the actuating medium, the inner ends of each having abutting shoulders to prevent the escape of the actuating medium, a bearing portion on the casing and a collar fixed on the shaft to take the end thrust, substantially as described.

In testimony whereof, I hereunto affix my signature in the presence of two witnesses.

HENRY F. WEINLAND.
